UNITED STATES PATENT OFFICE.

EDWARD H. CLIFFORD AND RICHARD SCHUMANN, OF DETROIT, MICHIGAN.

DESIGN FOR A WEDDING RING.

Application filed February 24, 1925. Serial No. 12,477. Term of patent 3½ years.

To all whom it may concern:

Be it known that we, EDWARD H. CLIFFORD and RICHARD SCHUMANN, citizens of the United States, residing in Detroit, in the county of Wayne and State of Michigan, have invented a new, original, and ornamental Design for Wedding Ring, of which the following is a specification, reference being had to the accompanying drawing, forming a part thereof.

Fig. 1 is an edge elevation of a wedding ring constituting our new design, Fig. 2 is a side view thereof, and Fig. 3 is a dia-grammatic view of the periphery.

We claim:

The ornamental design for a wedding ring as shown.

EDWARD H. CLIFFORD.
RICHARD SCHUMANN.
